ORA A. COLBY, OF IRWIN, PENNSYLVANIA, ASSIGNOR TO WESTINGHOUSE ELECTRIC & MANUFACTURING COMPANY, A CORPORATION OF PENNSYLVANIA.

ELECTRIC GLASS-ANNEALING FURNACE.

1,401,674.

Specification of Letters Patent. Patented Dec. 27, 1921.

Application filed April 7, 1920. Serial No. 372,019.

To all whom it may concern:

Be it known that I, ORA A. COLBY, a citizen of the United States, and a resident of Irwin, in the county of Westmoreland and 5 State of Pennsylvania, have invented a new and useful Improvement in Electric Glass-Annealing Furnaces, of which the following is a specification.

My invention relates to electric furnaces 10 and particularly to furnaces of the electric-resistance type and it has for one of its objects to provide an electric-resistance furnace for annealing glass objects which shall have a relatively low rate of deterioration 15 of the resistor and which may be operated for comparatively long periods of time at a relatively high temperature.

Another object is to provide a furnace of 20 this type with a resistor comprising solid blocks of refractory electrical-conducting material which shall be so located relative to each other as to cause a higher temperature at one end of the annealing chamber than will exist at the other end thereof.

25 Another object is to provide a construction for a furnace of the character indicated which shall permit of combining a number of such furnaces in a relatively small space, thus increasing the heat efficiency of the individual furnaces and having a relatively small number of terminal electrodes to conduct the current to and from all of the resistors.

In practising my invention, I provide one 30 or more annealing chambers in a refractory casing, a plurality of resistance blocks of solid refractory electrical-conducting material located in each of the chambers and constituting the top and bottom walls thereof, 35 wells or hoppers adjacent to the ends of the resistor blocks, granular electrical-conducting material in said hoppers, and terminal electrodes projecting into said hoppers to conduct the current to and from said resistor blocks.

In the single sheet of drawings, Figure 1 40 is a cross-sectional view, on the line I—I of Fig. 2, of a furnace embodying my invention, and Fig. 2 is a view of the furnace, 45 partly in cross-section, along the line II—II of Fig. 1, and partly in front elevation.

The supporting structure of the furnace 50 comprises an exterior metal casing or frame 1 in which is built an outer shell 2 of heat-insulating brick and an inner shell 3 of

highly refractory fire brick. The fire bricks 3 are spaced apart at substantially the center of the furnace to form a chamber 4. In the drawings, I have illustrated a double back-to-back furnace but this is not essential and the furnace may comprise one, two or even four such chambers when a furnace structure of substantially rectangular or circular cross-section is used, it is to be noted that the heat efficiency of two or of four 60 such operating chambers combined into a single structure is higher than when only one operating chamber is used because the exterior radiating surface of the combined structure is relatively small with a larger 65 number of operating chambers.

The resistor in each of the chambers 4 comprises two blocks or slabs of solid refractory electrical-conducting material such as carborundum or silicon-carbid, these 70 blocks being placed in a substantially horizontal position and so located that the rear edges of the two blocks are somewhat closer together than the front edges thereof. A mass 6 of plastic material, such as a mixture 75 of crucible clay and graphite with a suitable binder, is provided in each of the chambers 4 to hold the resistor blocks 5 in their proper relative positions. The mixture 6 is, of course, changed to a substantially 80 solid refractory condition as soon as the furnace is placed in operation. A cover member 7 closes the front side of each of the chambers 4 and is provided with a central 85 opening 8 through which a glass object, such as a lamp chimney 9, may be introduced and held between the resistor blocks 5.

The inner shell 3 is spaced apart to provide wells or hoppers 10 opposite and adjacent to the ends of the resistor blocks 5, 90 and the resistor blocks 5 are of such lengths as to project into the hoppers 10. Terminal electrodes 11 project into the hoppers 10 at the bottoms thereof and are provided with suitable metal terminal plates 12 to which 100 the electrical supply-circuit conductors 13 may be connected. A mass 14 of electrical-conducting granular material, such as graphite or coke, is placed in each of the hoppers 10 and is of relatively larger cross-section than the electrode 11 so that it 105 conducts the current from the electrode 11 to the resistor blocks 5 with a relatively small drop in voltage and, therefore, with a relatively small amount of heat generated there- 110

in. The finely divided granular material operatively engages the terminal electrode 11 and the resistor blocks 5 and provides a large number of contact paths through 5 which the current may flow from one to the other. Some oxidation of this granular material takes place during the operation of the furnace but, as the hopper 10 is open at its upper end, the granular material may 10 be easily repacked by means of a suitable stirring rod. Whenever required, the material to replace that which is consumed may be easily placed in the hoppers 10. A slab 15 of a suitable highly refractory material, such as carborundum, is placed between the resistor blocks 5 adjacent each of the hoppers 10 and prevents the granular material 14 entering the annealing chamber proper.

It is to be understood that any suitable 20 arrangement of metal terminal plates 12 and connections to the electrical supply circuit conductors 13 may be used as desired and that the sets of resistor blocks 5 in a plurality of furnaces may be connected either 25 in parallel or in series circuit relation, as may be suitable or desired.

I thus provide an electric-resistance furnace for annealing glass articles in which the resistor comprises solid blocks of refractory electrical-conducting material which may operate for relatively long periods of 30 time with relatively small deterioration and in which the method of conducting the current to and from the resistors insures that the furnace may be operated for relatively 35 long periods of time and still obtain good operative connection with the resistor blocks.

While I have shown a specific embodiment 40 of my invention, various changes may be made therein without departing from the spirit and scope of my invention, and I desire that only such limitations shall be placed thereon as are imposed by the prior art or are specifically set forth in the appended claims.

I claim as my invention:

1. In an electric furnace, the combination with a chamber, of a pair of resistor blocks of solid refractory electrical-conducting material constituting the top and bottom walls 50 of said chamber, the adjacent faces of said blocks being slightly divergent outwardly, means for holding said blocks in their operative positions, means for conducting current to and from said resistor blocks, and a cover member for said chamber having a central opening for the insertion of material to be heated.

2. In an electric furnace, the combination 60 with a chamber, of a resistor comprising

solid blocks of refractory electrical-conducting material constituting the sloping top and bottom walls of said chamber, means for holding said resistor blocks in their operative positions, hoppers adjacent the ends of 65 said resistor, terminal electrodes in said hoppers, a mass of electrical-conducting granular material in each of said hoppers interposed between the electrodes and said resistor to prevent overheating of said electrodes, and a cover member for the front of 70 said chamber having a central opening for the insertion of the material to be heated.

3. In an electric furnace, the combination with a chamber, of a resistor comprising 75 solid blocks of refractory electrical-conducting material constituting the top and bottom walls of said chamber, said blocks being so located relative to each other that the temperature at the rear of the chamber is higher 80 than that at the front of said chamber, means for holding said resistor blocks in their operative positions, hoppers opposite the ends of said resistor blocks, solid carbonaceous terminal electrodes located in said hoppers, masses of electrical-conducting granular material interposed between said electrodes and said resistor blocks, said masses of material being of greater cross-section 85 than the resistors to prevent over-heating of the electrodes, and a cover member for the front of said chamber comprising a solid block of refractory material having a central opening for the insertion of the material to be heated.

4. In an electric furnace, the combination with a plurality of spaced chambers, of a resistor for each chamber, comprising solid blocks of refractory electrical-conducting material constituting the top and bottom 100 walls, said blocks being so located relative to each other that the temperature at the rear of the chamber is higher than at the front thereof, means adjacent each chamber for holding said resistor blocks in their operative positions, hoppers opposite the ends of said resistor blocks, solid carbonaceous electrodes extending into said hoppers, masses of electrical-conducting granular material in said hoppers and adapted to conduct current from said electrodes to said resistor blocks, and a cover member for the front of each of said chambers comprising a solid block of refractory material having a central opening for the insertion of 105 the material to be heated.

In testimony whereof, I have hereunto subscribed my name this 30th day of March, 1920.

ORA A. COLBY.
